Serial No. 562,649

5 Claims. (Cl. 69—1)

My invention relates to an improvement in the method of and apparatus for manufacturing belts and has for one purpose the provision of a means and method for forming belts of a plurality of pieces of material, for example leather. One object is the provision of improved means for applying an adhesive to the separate belt pieces. Another object is the provision of improved means for applying pressure to the opposed portions of the pieces to be joined. Another object is the provision of improved means for feeding the belt, or the joined pieces of belt. Another object is the provision of improved control or operating means whereby an operator may actuate the various parts of the mechanism employed. Another object is the provision of improved timing means for timing the various operations. Other objects will appear from time to time in the course of the specification and claims.

I illustrate my invention more or less diagrammatically in the accompanying drawings, wherein—

Figure 1 is a general plan view;

Figure 2 is a general side elevation;

Figure 3 is a plan view of a unit of the adhesive treating means;

Figure 4 is a side elevation of the structure of Figure 3 with parts in section;

Figure 5 is a top plan view of the press actuating unit;

Figure 6 is a side elevation of the structure of Figure 5 illustrating the casing in section;

Figure 7 is a section on the line 7—7 of Figure 6;

Figure 8 is an end elevation of the reel mechanism;

Figure 9 is a partial end elevation showing the parts in a different position; and

Figure 10 is a detail.

Like parts are indicated by like symbols throughout the specification and drawings.

Referring to the drawings, A generally indicates any suitable supporting member, for example a table, upon which the pieces to be assembled may be positioned. It may include for example the legs or supports A¹ and the braces A². A³ is another similar table or support. A⁴ A⁵ indicate belt guiding arms, connected by a cross piece A⁶, which are adjustably mounted on a shaft or rod A⁷ at the outer end of the table A³. It will be understood that these arms may be adjusted apart to receive belt of varying width.

Positioned between the two tables is any suitable press structure. It may include for example the lower press body or base B, the supports B¹,

the upper press body B², the pressure cylinder B³, the plunger B⁴, and the press head proper B⁵. It will be understood that the members B² and B³ may have relative movement imparted thereto in any suitable manner, in order to effect pressure against articles positioned therebetween. Since the details of the press do not of themselves form part of the present invention the press is more or less diagrammatically indicated. Any suitable pressure source may be employed and I illustrate for example an inlet line B⁶ and an exhaust line B⁷ which may communicate with any suitable valve housing B⁸ in turn connected by the line B⁹ with the pressure chamber or member B³, whereby movement may be imparted to the press head B⁵.

C generally indicates a reel carriage which may include a base C¹ mounted for example on the rollers C². C³ C⁴ indicate any suitable upwardly extending supports upon which are mounted the bearing sleeve C⁴ in which is rotatably mounted any suitable reel shaft C⁵ which rotates the reel or drum C⁶. C⁷ are any suitable guide members which may be positioned upon the drum for example by penetration of the aperture C⁸, which permit adjustment of the members C⁷ to a variety of widths of belt. C⁹ indicates a detent ratchet wheel adapted to be engaged by the sliding pawl member C¹⁰, whereby undesired retrograde movement of the reel C⁶ is prevented. The end of the shaft C⁵ may be squared as at C¹¹.

D indicates a stop or abutment member having the extending sides D¹ D². The side D² is indicated as having thereon the A-frame D³ which includes the bearing sleeve D⁴ in which is rotatably mounted a shaft D⁵ having a terminal socket D⁶ apertured to receive the squared end C¹¹ of the shaft C⁵. The shaft D⁵ is of such length in relation to the bearing D⁴ that when it is advanced, for example manually, into the position in which it is shown in Figure 8, its aperture receives the member C¹¹ and thereby locks the reel carriage from movement away from the stop D. The shaft D⁵ may be kept in such locking relationship as for example by the hinged member D⁷ which fills the space between the enlargement D⁸ and the bearing sleeve D⁴, as shown for example in Figure 8. Thereby the reel C⁶ is maintained in operative relationship with the shaft D⁵. Mounted for rotation with the shaft D⁵ is the feed ratchet wheel D⁹ the teeth of which are engaged by the dog D¹⁰ which is pivoted to the pivot stirrup D¹¹. I will be understood that the stirrup D¹¹ is pivoted substan-

tially concentrically with the axis of rotation of the shaft D⁵. The stirrup may be moved by the control rod D¹¹ which in turn is pivoted to the control lever D¹² positioned adjacent the press. It will be understood that an operator standing at the press may advance or reel in on the reel C⁶ by drawing the upper end of the lever D¹² to the right, referring to the parts in the position in which they are shown in Figure 2. Thus a single operator may actuate the press and at the same time actuate the reel C⁶. It will be understood that in the use of the device a plurality of sheets of material E may be employed. Each such sheet, for example of leather, is bevelled on each end as at E¹, E² the bevels at opposite ends of each piece being preferably on opposite sides of the piece. In order to form the completed belt, and starting with one of the sections E, it may be laid in the position in which it is shown at the left of the table A, with the bevelled face E² up. Upon this bevelled face E² any suitable adhesive may be positioned, and then the bevelled face E¹ of the adjacent piece is laid upon it and the two joined pieces are advanced to the press to be subjected to pressure. In the ordinary operation of the device the belt so formed is reeled in on the reel C⁶ and the operator, before and after each pressing operation, actuates the lever D¹² to reel in the belt and draw the pieces into position in the press.

In practice I may employ sheets of celluloid as the adhesive. Whatever adhesive may be employed I find it advantageous to provide a sheet cut to about the right size for the lap joint between adjacent pieces of leather. The sheet material used as adhesive is normally inactive (not adhesive) and to render the same adhesive it is dipped or immersed into any suitable liquid or medium capable of rendering the sheet adhesive and it is then manually applied to the lap joint between the bevels E¹ and E² and the pieces so joined are then moved into the press to be pressed. In order to obtain a belt of uniform strength, uniformity in the applied adhesive and in the application of pressure is of vital importance. As an example of an advantageous adhesive I employ sheets of celluloid of controlled size and thickness. I may for example use a sheet of celluloid 5/1000 of an inch thick. Such sheet, before use, is immersed in an acetone bath and the timing of the immersion is of vital importance. With a sheet of celluloid of the above thickness an immersion of four seconds is satisfactory to properly soften the sheet and render it adhesive, and I provide means for automatically and precisely timing the immersion.

I may for example provide a tank or container G, as shown in Figures 1 and 2 and in greater detail in Figure 4. Positioned adjacent the tank G is a housing G¹ which may have a cover G² and a base plate G³⁰. The housing or casing is cut away as at G³. G⁴ indicates a bracket to which is pivoted a dipping lever G⁵ having an inner lever arm G⁶. The outer arm projects through the slot or aperture G³ and may terminate in any suitable clip including for example a fixed abutment G⁷ and an opposed leaf spring G⁸, adapted between them to grasp the adhesive sheet G⁹. G¹⁰ is any suitable knob for convenience in manual operation. The lever or dip arm G⁵ is normally held in the position in which it is shown in dotted line in Figure 4, as by the spring G¹¹. When the operator

wishes to employ the device he may manually clip or insert the adhesive sheet G⁹ and he then presses down on the knob G¹⁰, thrusting the device into the full line position, and thereby inserting the sheet G⁹ in the acetone bath present in the container G. When he so inserts the device the arm G⁶ extends the spring G¹¹ and itself passes over the forward stop end H¹ of the cam and stop lever H which is pivoted as at H² on the bracket H³ and which is normally held in the full line position in which it is shown in Figure 4, as by the spring H⁴. As long as the parts are in the full line position of Figure 4 the sheet G⁹ is held beneath the surface of the acetone bath.

J indicates any suitable motor with a pinion J¹ in mesh with the gear J² which in turn rotates a pinion J³ in mesh with a second gear J⁴ which in turn controls the cam wheel J⁵ carrying the cam projection J⁶. The wheel and cam projection are aligned with the cam portion H⁵ of the lever H. Normally this portion H⁵ engages the periphery of the wheel J⁵, which holds the stop member H¹ in the full line position of Figure 4 and keeps the sheet G⁹ in the acetone bath. The actuating circuit for the motor J includes the lines J⁷, J⁸ which circuit may be closed by any suitable switch J⁹ which in turn is actuated by a contact J¹⁰ engaged by an opposed adjustable contact J¹¹ upon the arm J¹² which is associated with the dip arm or lever G⁵. Thus, when the operator depresses the knob G¹⁰ to position the sheet G⁹ within the liquid he at the same time closes the motor circuit and the motor, through the above described gear reduction, rotates the cam wheel J⁵ until the cam projection J⁶ engages the member H⁵ and flips the member H¹ up past the portion G⁶ of the lever G⁵. This permits the spring G¹¹ to actuate and draw down on the lever G⁶, thus raising the lever G⁵ to the dotted line position and withdrawing the sheet G⁹ from the bath. This at the same time breaks the motor circuit and leaves the parts in position for the next cam excursion. J¹³ indicates an air recoil cylinder with a plunger therein associated with the shaft J¹⁴ which in turn is pivoted as at J¹⁵ to the lever G⁵, whereby the upward movement of the dip arm is cushioned. The air recoil cylinder is effective to prevent an unduly sudden withdrawal of the lever G⁵ and the sheet G⁹ from the bath. I thereby obtain a precisely timed immersion of the sheet G⁹ into the bath and the operator then withdraws the treated sheet from the clip and places it upon the lap joint between two adjacent belt pieces E. He then actuates the reel C⁶ in the earlier described manner, by employment of the lever D¹² and positions the joint within the press.

It is of great importance that the time of subjection to pressure be uniform and I therefore provide timing means for controlling the time of subjection to pressure and for causing the pressure to release. Positioned upon the fixed press head B² I illustrate a housing or casing K having an upward and outward top or extension K¹. K² indicates a motor which drives a cam shaft K³ through a gear reduction including pinion K⁴, gear K⁵, pinion K⁶ and gear K⁷. Any suitable bearing means may be provided for the various parts of the gear reduction. Mounted for rotation with the cam shaft K³ is the cam roller or wheel K⁸ with the cam projection K⁹.

It will be understood that any suitable three way valve is positioned within the valve housing B⁸. This valve may be controlled by any suitable

exterior stem L. Secured to the valve stem is the arm L¹ which is provided with a manual handle L². The valve stem is operated by rotation and it is understood that the arm L¹ and the handle L² therefore rotate about the longitudinal axis of the valve stem, incidentally rotating the valve stem as they are rotated. L³ indicates any suitable stop means for limiting one outer end of the arc of rotation of the arm L¹. The other end of the arm L¹ is provided with a contact plate L⁴ which may be opposed to the tail L⁵ of the cam lever L⁶, the opposite end L⁷ of the cam lever engaging the cam roller K⁸ and the cam projection K⁹. The cam lever is pivoted intermediate its ends as at L¹⁰ on any suitable bracket L¹¹, and is normally held in the full line position in which it is shown in Figure 7, as by the coil spring L¹². L¹³ is any suitable emergency manual control lever the purpose for which will later appear. It is also pivoted as at L¹⁰ and includes an inner arm L¹⁴ with a contact member L¹⁵ engaging the tail L⁵ of the cam lever. It will be understood that this manual control member L¹³ may be employed to depress the portion L⁵ of the cam lever L⁶ to clear the member L⁴ and thereby to release the cam for rotation and to release the arm L¹ for rotation into the dotted line position. L¹⁵ indicates a pad or cushion upon the abutment bracket L³. It will be understood that the spring M normally tends to hold the arm L¹ in the dotted line position and in fact always tends to lift the arm when it is in full line position, to the limit of the stop L⁵. M¹ indicates a switch in a circuit including the lines M² M³ in which circuit the motor K² is included. M⁴ M⁵ indicate the leads to the power line and M⁶ a manually operable switch whereby the power for the device may be shut off.

In the operation of the device at the beginning of the excursion of the press, before pressure is admitted to actuate the press the parts are in the dotted line position of Figure 6 with the handle L² in generally horizontal position. When the operator wishes to exert pressure he manually moves the handle L² to the full line position and thereby depresses the arm L¹, against the spring M, to the full line position in which it is shown in Figure 6. He thereby closes the switch M¹ by forcing the contact M⁷ associated with the arm L¹ against the actuating switch member M⁸. This closes the circuit for the motor K² and initiates the rotation of the cam roller K⁸. When the cam roller starts its rotation, the parts are in the full line position of Figure 7. It effects a complete revolution and the cam member K⁹ then kicks up the opposed portion L⁷ of the cam lever and thereby frees the opposite end L⁵ from the end of the arm L¹. The spring M then swings the arm L¹ back into the dotted line position. It will be understood that when the operator swings the arm L¹ into the full line position he thereby opens the inlet B⁶ and admits the pressure to the chamber B³, thus actuating the press. At the end of one revolution of the cam roller K⁸ the arm L¹, being released, and drawn by the spring M into inoperative position, this release and rotation of the arm closes the inlet B⁶ and opens the exhaust B⁷ and permits the press head B⁵ to drop into lower or inoperative position. The gear reduction is so proportioned as to cause actuation of the press for any desired period, the timing being uniform. For example about 15 seconds in the press is effective for the employment of the adhesive above discussed. The motor K² imparts such rotation

to the cam roller K⁸ that at the end of 15 seconds the cam releases the control lever or arm L¹, which is then drawn by the spring M into inoperative position. Thus the operator by one movement of the control handle L² not only actuates the press, but also actuates the timing means which causes the press to release at the end of the desired period.

During this period of, for example, 15 seconds, the forward end of a given strip of leather is gripped by the press and pressure is being applied to the lap joint which has last been previously treated with one of the immersed adhesive sheets. During this 15 second interval the operator applies the cement or adhesive to the free end of the clamp belt strip and presses the forward end of the next following belt strip on it. When the press releases, the operator actuates the reel C⁶ and winds in the finished belt upon the reel, thus drawing the belt section which was last cemented forwardly across the surface of the second table A³ and at the same time positioning the joint about to be pressed in alignment with the press. Thus a single operator is performing three functions, namely, reeling in the finished belt, actuating and timing the press, and applying the cement for the joint next to be pressed. This positive timing enormously speeds up the process of belt manufacture. It also insures a uniform product, as every joint is treated with an identical cement and is subjected to an identical pressure for an identical period. The work of the operator is simplified in controlling the press, since he has to make but a single movement, the actuating movement, which also starts the timing mechanism. His work in preparing the cement is correspondingly simplified, as the celluloid sheet is automatically withdrawn at the proper instant. Finally, the employment of distant control for reeling in the belt saves the operator many steps and consequently speeds up the operation.

When sufficient belt has been reeled in upon one of the reels C⁶, or when a run of belt is completed, the operator, or a second operator, may bodily remove the reel C⁶ and its supporting structure by dropping the member D⁷ into the position in which it is shown in Figures 9 and 10. The shaft D⁵ is then moved away from the reel C⁶, freeing the squared end C¹¹ of the shaft C⁵. The operator can then wheel the carriage C bodily away. It will be noted that the reel actuating mechanism is on a fixed base and therefore is not removed with the reel, and a new reel, with its supporting base or truck, can be wheeled into place almost instantaneously if necessary.

The function of the emergency control lever L¹³ is to permit manual release of pressure prior to the time at which it will be released by the automatic control means. In other words the manual lever L¹³ can be employed to do at any time what the cam member K⁹ does at a particular time interval.

It will be realized that whereas I have described and shown a practical and operative device, nevertheless many changes may be made in size, shape, number and disposition of parts without departing from the spirit of my invention. I therefore wish my description and drawings to be taken as in a broad sense illustrative and diagrammatic rather than as limiting me to my specific showing. In particular I do not wish to be limited to the employment of any specific adhesive or thickness of adhesive or to any specific bath as a variety of adhesives and a variety of baths may be

employed. Also, the details of press, reel and supporting table may be widely varied.

I claim:

1. In a belt manufacturing mechanism, a press and means for actuating it, and control means for the press including a manually operable handle and means actuated by the handle for terminating the operation of the press a predetermined time after actuating of the handle, including means tending normally to move the handle to inoperative position, restraining means adapted to resist said last mentioned means, and means for rendering said restraining means inoperative, including a motor and a circuit therefor, and means for closing said motor circuit when the handle is moved into operating position.
2. In a belt manufacturing mechanism, a press and means for actuating it, and control means for the press including a manually operable handle and means actuated by the handle for terminating the operation of the press a predetermined time after actuation of the handle, and additional manually operable control means for terminating the operation of the press at any time.
3. The method of manufacturing belts by joining in succession shorter pieces of leather to each other to form a longer piece, which includes subjecting an inactive adhesive sheet to immersion for a predetermined period in a liquid softening medium, terminating said immersion and said period at a predetermined time in relation to the application of pressure to the joints between the individual pieces of leather, applying, substantially immediately upon the termination of its immersion, said sheet to a joint between adjacent pieces of leather to be joined, thereafter and substantially immediately subjecting said joint to pressure, maintaining said pressure for a determined time, and thereafter advancing the joint so formed from the zone of pressure and continuing the process by similarly joining additional pieces of material to the belt so formed, and so timing the periods of pressure and the periods

45

of immersion that when one joint has been completed and advanced from the pressure zone an adhesive sheet is ready for immediate application to the ensuing joint.

4. The method of manufacturing belts by joining in succession shorter pieces of material to each other to form a longer piece, which includes subjecting an inactive adhesive sheet to immersion for a predetermined period in a medium capable of rendering said sheet adhesive, thereafter, within a predetermined period, applying said adhesive sheet to a joint between adjacent pieces of material, thereafter substantially immediately subjecting said joint to pressure and terminating said pressure after a predetermined period, and similarly joining the ensuing pieces, and so timing the initiation of pressure and the initiation of immersion that when one joint has been completed and freed from the zone of pressure the adhesive sheet for the ensuing joint is ready for immediate application thereto immediately prior to subjection of the joint to the ensuing pressure.
5. The method of manufacturing belts by joining in succession shorter pieces of material to each other to form a longer piece, which includes subjecting an inactive adhesive sheet to immersion for a predetermined period in a liquid softening medium, thereafter, within a predetermined period, applying said adhesive sheet to a joint between adjacent pieces of material, thereafter substantially immediately subjecting said joint to pressure and terminating said pressure after a predetermined period, and manually moving the belt forwardly through the zone of pressure after the termination of said pressure, and similarly joining the ensuing pieces, and so timing the initiation of pressure and the initiation of immersion that when one joint has been completed and freed from the zone of pressure the adhesive sheet for the ensuing joint is ready for immediate application thereto immediately prior to subjection of the joint to the ensuing pressure.
